CLAIM

The ornamental design for a rebar cage spacer wheel, as shown and described.

DESCRIPTION

FIG. 1 is a perspective illustration one half of the rebar cage spacer wheel, with the other wheel half being identical thereto;

FIG. 2 is a left side view of the assembled wheel, with the opposite side being identical thereto;

FIG. 3 is a plan view of a wheel half;

FIG. 4 is a side view of the wheel half, showing the diametrical surface that confronts the diametrical surface of the opposite wheel half;

FIG. 5 is a plan view of the opposite side of the wheel half illustrated in FIG. 3;

FIG. 6 is an end view of a wheel half, with the opposite end being identical thereto; and,

FIG. 7 is a plan view of the rebar cage spacer wheel fully assembled with the opposite plan view being a mirror image.

The claimed design is shown detached in FIGS. 1 and 3-6 for clarity of illustration.

FIG. 1
